CHANGE-SPEED MECHANISM.

1,001,354.

Specification of Letters Patent. Patented Aug. 22, 1911.

Application filed June 4, 1910. Serial No. 565,183.

To all whom it may concern:

Be it known that I, FRANK M. CHAPMAN, a citizen of the United States, having a residence and post-office address at Hudson Falls, county of Washington, State of New York, have invented certain new and useful Improvements in Change-Speed Mechanism; and I do hereby declare the following to be a full, clear, and exact description of the invention, such as will enable others skilled in the art to which it appertains to make and use the same.

My invention has for its object to provide means for driving a shaft from a pulley, or vice versa, and also for varying the speed of transmission and for interrupting the driving when desired.

In the accompanying drawings, Figure 1 represents a longitudinal section, partly in side elevation, of a shaft and pulley adapted to be driven the one from the other, as the case may be, in accordance with my invention; Fig. 2 represents a plan view thereof; Fig. 3 represents a vertical transverse sectional elevation, taken on a plane indicated by the line 3—3 of Fig. 1; Fig. 4 represents a vertical transverse sectional elevation, taken on a plane indicated by the line 4—4 of Fig. 1; Fig. 5 represents a vertical transverse sectional elevation, taken on a plane indicated by the line 5—5 of Fig. 1; and Fig. 6 represents a plan view, partly in section, of certain of the parts to illustrate their mode of operation.

Similar numerals of reference indicate similar parts throughout the several views.

Although, as hereinbefore stated, the invention is equally applicable to the driving of a pulley from a shaft or the driving of a shaft from a pulley, it may be assumed, for purposes of simplicity of description, that the driving element is the pulley 1, and that the driven element is the shaft 2. The pulley is shown as mounted loosely upon the shaft, so as to rotate freely thereon, and is provided internally with a gear track-way 3.

The track-way 3 intermeshes with gears 4 of a pair of cones 5, which cones are adapted to rotate freely upon shafts 6. The shafts 6 constitute part of a frame, whose other members consist of the end plate 9, and the spider 7, whose hub 8 is splined or otherwise fixed to the shaft 2.

Intermediate of the rotatable cones 5 is located the non-rotating cone 10 which is

mounted on the shaft 2 in inverted position with respect to the rotatable cones. The non-rotating cone 10 is mounted loosely upon the shaft 2 and not only does not take part in the rotation of the shaft 2, but is shiftable longitudinally thereon. Normally, the non-rotating cone 10 is held in the driving position indicated in Figs. 1 and 2, by means of a spring 11 which reacts between an adjustable collar 12 and a sleeve 13, which sleeve is attached to and forms a projection from the non-rotating cone.

Upon the sleeve 13 is mounted the sliding collar 14 having side straps 15 (see Fig. 2) which connect it to an actuating hand lever 16 pivoted to any suitable fixed point of support 17 by means of a pin 18 and a loose-motion slot 19. The hand lever is provided with a spring latch 20 having a releasing handle 21, and the spring latch 20 is adapted to engage behind the flange 22 of a collar 23 fixed upon the shaft 2, so as to retain the hand lever in its extreme outward position of adjustment, as will be hereinafter more fully set forth.

The collar 14 engages a cross-plate, made up in part of the ring 24 and the spring metal projections 25. At the outer ends of the spring metal projections 25 are fixed the rods 26 carrying belt pulleys 27 and passing through the forked or notched ends 28 of the plate 9. The belt pulleys 27 support an endless belt 29 and this belt passes between the non-rotating cone 10 and the rotatable cones 5 and engages with their peripheries, as shown.

The parts being constructed and arranged as described, the mode of operation of the invention is as follows: Power derived from the driving pulley 1 is communicated to the cones 5 through the intermediacy of the gear track-way 3 and the gears 4 and maintains the cones 5 in constant rotation upon the shafts 6. This motion of rotation of the cones 5, however, is not transmitted to the shaft 2 unless the non-rotating cone 10 is at its inner adjustment, as indicated, for instance, in Figs. 1 and 2. It is held, normally, in this inner adjustment by means of the spring 11, so that the upper and lower strands of the endless belt 29 are gripped between the non-rotating cone and the rotatable cones 5. The cones 5 will thereupon travel bodily about the cone 10, carrying with them the entire frame of which the

spider 7 and its hub 8 form part, and thereby driving the shaft 2; it being understood that except for the presence of the endless belt 29, the cones 5 would merely revolve 5 about their shafts 6 without imparting rotary motion to the frame and the shaft 2. The speed with which the shaft 2 is revolved, under these circumstances, will depend upon the position of the belt 29 along 10 the length of the cones, the means provided sufficing to shift the belt so as to place it at any place along the length of the cones from the larger ends of the cones 5 to the smaller ends thereof. To this end, when it is de- 15 sired to speed up the shaft 2, the hand lever 16 will be moved toward the left, where- upon the collar 14 will slide along the sleeve 13 and will carry with it the ring 24, plates 25 and rods 26, thereby correspondingly 20 moving the belt 29 toward the left and to a position where the ratio of transmission between the cones 5 and the shaft 2 will be increased. Conversely, the farther the belt is moved toward the smaller ends of the cones 25 5, by shifting the lever 16 toward the right, the less will be the ratio of transmission between the cones 5 and the shaft 2, and the slower will be the speed of the shaft. When it is desired to entirely interrupt the trans- 30 mission between the pulley and the shaft, the hand lever 16 will be shifted to the right to such an extent that the collar 14 will en- 35 gage a fixed collar or like projection 31 upon the sleeve 13. Consequently the sleeve 13 and with it the non-rotating cone 10 will be moved toward the right in opposition to the spring 11 and consequently the space between the cone 10 and the rotating cones 5 will be so widened that the endless belt 40 will not be gripped between the oppos- ing surfaces. Transmission of motion will thereby be entirely interrupted and the cones 5 will cease to revolve about the non- 45 rotating cone 10 and will merely rotate upon their own shafts 6. In order to re- 50 tain the parts in the non-transmitting adjustment, the spring latch 20 will drop behind the flange 22 on the set collar 23, and, when subsequently released, to reestablish transmission, the spring 11 will return the 55 non-rotating cone 10 to its original position. The collar 12 may be adjusted so as to vary the tension of the spring 11, as may be de- sired.

60 It will be understood that, in the particular embodiment of the invention illus- trated in the drawings, the non-rotation of the cone 10 is assured, by reason of the circum- 65 stance that the sleeve 13 is splined by the feather 32 to the sliding collar 14, which collar is itself held against rotation by rea- son of its connection through the hand lever 16 with the point of support of said hand lever.

65 It will be apparent that as the endless

belt 29 is shifted toward the right, it be- 70 comes progressively more and more ex- tended by the non-rotating cone, and that therefore some provision is required in order to meet this contingency. To this end, 75 the belt 29 may be made of correspondingly elastic material, or the necessary take-up and expansion can be obtained by the in- 80ward and outward flexure of the spring metal projections 25. In Fig. 6, for in- 85 stance, the inward flexure of these spring plates is indicated for the adjustment of the endless belt corresponding to its shift to practically the extreme outer end of the non-rotating cone 10.

Having thus described my invention, what I claim is:

1. The combination with a shaft and a pulley to be driven the one from the other, of a frame connected to the shaft, cones mounted to rotate on the frame, a driving connection between the pulley and cones, a non-rotating cone intermediate of the rotatable cones, an endless belt passing between and engaging the rotatable cones and the non-rotating cone, means for shifting the belt so as to engage the cones at various points along their length, and means for shifting the non-rotating cone so as to interrupt the drive when desired; substan- 90 tially as described.

2. The combination with a shaft and a pulley to be driven the one from the other, of a frame connected to the shaft, cones mounted to rotate on the frame, a driving connection between the pulley and cones, a non-rotating cone intermediate of the rotatable cones, an endless belt passing between and engaging the rotatable cones and the non-rotating cone, and means for shifting the non-rotating cone so as to interrupt the drive when desired; substan- 100 tially as described.

3. The combination with a shaft and a pulley to be driven the one from the other, of a frame connected to the shaft, cones mounted to rotate on the frame, a driving connection between the pulley and cones, a non-rotating cone intermediate of the rotatable cones, an endless belt passing between and engaging the rotatable cones and the non-rotating cone, means for shifting the non-rotating cone so as to interrupt the drive when desired, and means for retaining the non-rotating cone in its shifted position; substan- 110 tially as described.

4. The combination with a shaft and a pulley to be driven the one from the other, of a frame connected to the shaft, cones mounted to rotate on the frame, a driving connection between the pulley and cones, a non-rotating cone intermediate of the rotatable cones, an endless belt passing between and engaging the rotatable cones and the non-rotating cone, means for shifting the non- 125 rotating cone so as to interrupt the drive when desired, and means for shifting the 130

non-rotating cone so as to interrupt the drive when desired, and a spring for returning the non-rotating cone to reestablish the drive; substantially as described.

5 5. The combination with a shaft and a pulley to be driven the one from the other, of a frame connected to the shaft, cones mounted to rotate on the frame, a driving connection between the pulley and cones, a 10 non-rotating cone intermediate of the rotatable cones, an endless belt passing between and engaging the rotatable cones and the non-rotating cone, and means for shifting the belt so as to engage the cones at various 15 points along their length, said means consisting of a collar, a cross-plate engaged by the collar, rods carried by the cross-plate, bearing rollers for the endless belt mounted on the rods, and an actuating lever connected to the collar; substantially as described.

6. The combination with a shaft and a pulley to be driven the one from the other, of a frame connected to the shaft, cones mounted to rotate on the frame, a driving connection between the pulley and cones, a 25 non-rotating cone intermediate of the rotatable cones, an endless belt passing between and engaging the rotatable cones and the non-rotating cone, and means for shifting the belt so as to engage the cones at various 30 points along their length, said means consisting of a collar, a cross-plate engaged by

the collar, rods carried by the cross-plate, bearing rollers for the endless belt mounted 35 on the rods, and an actuating lever connected to the collar, the cross-plate being of spring metal so as to permit the bearing rollers to recede or approach each other as the belt is shifted; substantially as de- 40 scribed.

7. The combination with a shaft and a pulley to be driven the one from the other, of a frame connected to the shaft, cones mounted to rotate on the frame, a driving 45 connection between the pulley and cones, a non-rotating cone intermediate of the rotatable cones, an endless belt passing between and engaging the rotatable cones and the non-rotating cone, a sleeve connected to the 50 non-rotating cone and shiftable longitudinally on the shaft, a spring reacting against the sleeve and normally holding the non-rotating cone in driving engagement, a collar mounted on the sleeve, a cross-plate en- 55 gaged by the collar, rods carried by the cross-plate, bearing rollers for the endless belt mounted on the rods, and an actuating lever connected to the collar; substantially as described.

In testimony whereof I affix my signature, in presence of two witnesses.
